HEEL FOR BOOTS OR SHOES

Harold C. Nimrick, Detroit, Mich.

Application July 16, 1943, Serial No. 495,810

3 Claims.

(CL 36—59)

This invention relates to heels for boots or shoes the object being to provide the replaceable insert of rubber like character introducible into a recess provided therefor in the heel to prevent wear at a side or end thereof.

Boot and shoe heels whether formed of leather or rubber become worn usually on the outer rear side of the heel and a feature of my invention is to provide a replaceable insert of rubber or other flexible material introducible in a recess or in recesses provided in the shoe heel at the rear or rear side to locked relation therein and having a thin flange overlying the heel surface about the periphery of the recess.

These and other features and objects of the invention are hereinafter more fully described and claimed and the preferred form of a heel protector embodying my invention is shown in the accompanying drawing in which—

Fig. 1 is a plan view of the wearing surface of the heel showing my improved inserts positioned therein.

Fig. 2 is a side elevation of Fig. 1.

Fig. 3 is a section taken on line 3—3 of Fig. 1.

Fig. 4 is a similar section showing an alternative form of insert.

My improved insert may be used with heel elements formed of leather, rubber or other suitable material and in the form of the insert for use in conjunction with a rubber heel I provide the heel element 1 with a number of recesses preferably three, as shown at 2 in Fig. 3.

In the forming of the rubber heel 1 I preferably, but not necessarily, provide a metal plate 3 having a central aperture of approximately the same diameter as the body of the insert at a distance from the inner end of the recess. The recess at its inner end is somewhat larger in diameter than the body of the opening indicated at 2 and the insert has an inner end 5 of greater diameter than the body and forming a flange providing a shoulder 6 which engages the inner surface of the plate. This flange normally prevents accidental removal of the insert in ordinary conditions of use. The insert further has a flange 7 of desired thickness overlying the lower surface of the heel and serves to not only provide a cushioning effect in the use of the boot or shoe by the wearer but also prevents wear of that portion of the heel surface having the inserts.

The insert has a central longitudinal recess 8 open through the outer wearing face of the insert and the purpose of such recess is to provide a collapsible body to permit the shoulder portions 6 to turn inwardly toward the center as the insert 55

is being introduced into the recess to final position in the heel and, as the flange portion 6 is inserted to final position, the shoulder portion expands into the recess beneath the plate and serves to prevent accidental removal of the insert in the normal use of the boot or shoe.

In Fig. 4 I have shown a heel portion 9 formed of leather and having a recess provided with an enlarged portion 10 at its bottom into which the rim 11 of the insert engages when in final position therein. The insert shown in Figs. 3 and 4 are similar in construction and each involve the central recess to provide a collapsible body permitting the rim or flange 11 to turn inwardly as it is passed into the heel recess. The metal plate shown at 3 in Fig. 3 may be used with a leather heel shown in Fig. 4 but preferably is not so used as the leather itself is sufficiently rigid to provide a shoulder preventing withdrawal of the insert in the normal use of the heel.

The recess 8 is of utility in introduction of the rubber insert into the heel recess in that it not only permits the flanged end portion of the insert to turn inwardly as it is passed into the heel recess but also enables the use of any element such as a match stick of less cross sectional area than that of the recess whereby pressure may be exerted upon the inner end of the insert to insure the forcing of the said end to proper position therein. Without such provision of the recess 8 it would be difficult to force the inner end of the recess to final position by reason of the fact that the rubber is compressible and the inner flange being of larger diameter than the body of the heel recess it might not be forced to final position by pressure applied to the outer end.

It is believed evident from the foregoing description that the heel element may be sold with the inserts therein and as the inserts become worn new inserts may be introduced thereinto and it is therefore contemplated to provide for sale of the heel element and inserts or of the inserts alone as replacements for worn inserts.

The inserts are quite inexpensive and thus by replacement of worn inserts the heels may be used indefinitely by replacing the worn inserts as the heel itself does not require to be replaced. Heretofore the entire heel element required to be replaced after becoming worn whether the heel element be formed of rubber, leather or other character of material.

In either case the rubber inserts not only serve to prevent wear of the heel but also provide a shock absorbing means beneficial to the wearer and if the heel element be made of leather the

rubber insert not only reduces the shock but prevents slipping when walking on hard surfaces.

It is believed evident from the foregoing description and the drawing that the various features and objects of the invention are attained by the structure described and shown and that various changes may be made in the structure and relationship of parts without departing from the spirit and scope of the appended claims.

Having thus briefly described my invention, its utility and mode of operation, what I claim and desire to secure by Letters Patent of the United States is:

1. A boot or shoe heel comprising a heel element having cylindrical recesses therein opening through the tread surface thereof and having at its inner end an enlarged portion providing a shoulder adjacent the bottom of the recess, a metal plate having an aperture of the same diameter as that of the recess and overlying the said shoulder, an insert of flexible material having a body approximately of the same cross sectional area as that of the recess and an inner end portion having an outwardly inclined side wall providing a flange of greater peripheral dimension than the body to engage the portion of the metal plate opposite the surface thereof engaging the shoulder of the recess providing a means normally preventing withdrawal of the insert in its normal use, said body further having a thin flange providing in association with the body a flat resilient disc overlying the outer surface of the heel.

2. A boot or shoe heel comprising a heel element having recesses therein opening through the

tread surface thereof, each recess having an enlarged inner end, providing a shoulder adjacent the bottom of the recess, a rubber insert having a body portion of approximately the same cross sectional area as that of the heel recess, said insert having a recess opening through its outer end and an inner end portion formed to provide a flange having an outwardly inclined side wall of greater peripheral dimension than the body of the insert to engage beneath the shoulder of the recess, the arrangement providing that in introducing the insert into the heel recess, the flange portion of the insert may be compressed inwardly and when seated in the heel recess may expand into the enlarged end of the recess.

3. A boot or shoe heel comprising a heel element having a cylindrical recess opening through the wear surface thereof, said recess having an enlarged portion at its inner end within the heel body, said insert being formed of a flexible material having a cylindrical body and a terminal portion at one end of circular form of greater diameter than the body and having the form of a truncated cone, said body having a recess extending inwardly from the outer end of the body and terminating approximately a distance from the flanged end practically equal to the thickness thereof, and the outer end having an enlarged comparatively thin flange overlying the wear surface of the heel and further having an axial recess opening through the outer face thereof.

HAROLD C. NIMRICK.
